United States Patent Office

Des. 232,541
Patented Aug. 27, 1974

232,541

PUBLIC TELEPHONE SUPPORT

Keith David Bartley, 6250 Brokenhurst Road 46220;
and Fred Arlington Dewhirst, 5313 E. Winston Drive
46226 both of Indianapolis, Ind.; Donald Michael Genaro, 501 Constant Ave., Haworth, N.J. 07641;
and John Niel McGarvey, 731 Cornell Ave., Drexel
Hill, Pa. 19026

Filed June 5, 1972, Ser. No. 260,064

Term of patent 14 years

Int. Cl. D25—99
U.S. Cl. D13—1 L

FIG. 1

FIG. 2

FIG. 3

FIG. 4

FIG. 5

FIG. 6

FIG. 7

FIG. 8

FIG. 1 is a perspective view of the basic form of our design for a public telephone support wherein the support is free-standing;

FIG. 2 is a reduced rear view of the basic form;

FIG. 3 is a front view of the basic form;

FIG. 4 is a side view of the basic form, the opposite side having substantially the same appearance;

FIG. 5 is a perspective view of a second form of our design for a public telephone support wherein the support is free-standing and includes a shelf and a shallow base;

FIG. 6 is a reduced rear view of the second form;

FIG. 7 is a front view of the second form; and

FIG. 8 is a side view of the second form, the opposite side having substantially the same appearance.

The broken line portions are shown for illustrative purposes only and do not comprise part of the design.

We claim:

The ornamental design for a public telephone support, substantially as shown and described.
